UNITED STATES PATENT OFFICE.

ALEXANDER FRIEDMAN, OF PITTSBURGH, PENNSYLVANIA, ASSIGNOR TO PENNSY WATCH COMPANY, OF PITTSBURGH, PENNSYLVANIA, A CORPORATION OF DELAWARE.

DESIGN FOR A TOP PLATE FOR WATCH-MOVEMENTS.

55,265.

Specification for Design.

Patented May 25, 1920.

Application filed September 3, 1919. Serial No. 321,471. Term of patent 7 years.

To all whom it may concern:

Be it known that I, ALEXANDER FRIEDMAN, a citizen of Hungary, residing at Pittsburgh, in the county of Allegheny and State of Pennsylvania, United States of America, have invented a new, original, and ornamental Design for a Top Plate for Watch-Movements, of which the following is a specification, reference being had to the accompanying drawing, forming part thereof.

The figure is a plan view of a top plate for watch movements, showing my new design.

I claim:

The ornamental design for a top plate for watch movements, substantially as shown.

ALEXANDER FRIEDMAN.
